UNITED STATES PATENT OFFICE.

LAWRENCE VICTOR DAVIS, OF SOUTH BEND, INDIANA, AND ATWOOD L. BOGGS, OF BROOKLINE, MASSACHUSETTS, ASSIGNEES TO PERFECTION COOLER COMPANY, OF STOUGHTON, MASSACHUSETTS.

DESIGN FOR A COOLER.

Application filed March 24, 1925. Serial No. 12,858. Term of patent 14 years.

To all whom it may concern:

Be it known that we, 1, LAWRENCE VICTOR DAVIS and 2, Atwood L. Boggs, citizens of the United States, residing at 1, South Bend, 2, Brookline, in the counties of 1, St. Joseph, 2, Norfolk, and States of 1, Indiana, 2, Massachusetts, have invented a new, original, and ornamental Design for Coolers, of which the following is a specification, reference being had to the accompanying drawing.

In the accompanying drawing:

The figure is a side elevation of the cooler, showing our new design.

We claim:

The ornamental design for a cooler, as shown.

In testimony whereof, we hereto affix our signatures.

LAWRENCE VICTOR DAVIS.
ATWOOD L. BOGGS.
